CLAIM

We claim the ornamental design for a media player docking station for bathing unit or boat, as shown and described.

DESCRIPTION

FIG. 1 is a perspective view of a first embodiment of a media player docking station for bathing unit or boat, embodying our new design;

FIG. 2 is a front elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is an alternate front elevation view thereof, with the cover shown in an open position;

FIG. 8 is a rear elevation view thereof;

FIG. 9 is a perspective view of a second embodiment of a media player docking station for bathing unit or boat, embodying our new design;

FIG. 10 is a front elevation view thereof;

FIG. 11 is a left side elevation view thereof;

FIG. 12 is a right side elevation view thereof;

FIG. 13 is a bottom plan view thereof;

FIG. 14 is a top plan view thereof;

FIG. 15 is an alternate front elevation view thereof, with the cover shown in an open position;

FIG. 16 is a rear elevation view thereof;

FIG. 17 is a perspective view of a third embodiment of a media player docking station for bathing unit or boat, embodying our new design;

FIG. 18 is a front elevation view thereof;

FIG. 19 is a left side elevation view thereof;

FIG. 20 is a right side elevation view thereof;

FIG. 21 is a bottom plan view thereof;

FIG. 22 is a top plan view thereof;

FIG. 23 is an alternate front elevation view thereof, with the cover shown in an open position; and,

FIG. 24 is a rear elevation view thereof.

The broken lines represent the portions of the design that form no part of the claim.
